IRONING MACHINE CONTROL

William H. Bradley, Fort Wayne, Ind., assignor
to Horton Manufacturing Company, Fort
Wayne, Ind., a corporation of Indiana

Application February 9, 1946; Serial No. 646,672

1 Claim. (Cl. 38—61)

1

The invention relates generally to ironing machines and more particularly to the control means therefor.

The general object of the invention is to provide an ironing machine comprising a pair of relatively shiftable ironing elements, one of which is a roll, and power driven mechanism adapted to effect such shifting movement and to drive the roll, with a novel control member readily adjustable into any of a plurality of positions to permit actuation thereof by the operator in a manner most convenient to the operator.

More specifically, it is an object to provide an ironing machine of the foregoing character, having a novel control member readily adjustable relative to the machine so that it may be actuated either by the operator's hand, elbow or knee.

Another object is to provide an ironing machine of the foregoing character, having a novel control member readily adjustable relative to the machine into one position for actuation by the operator's knee, or into another position for actuation by her elbow, or into a plurality of other positions for actuation by her hand, to facilitate ironing of different types of articles.

A further object is to provide an ironing machine of the foregoing character, having a control member normally adapted for manual actuation but so constructed that a foot control device may be readily connected thereto.

Other objects and advantages will become apparent from the following description taken in connection with the accompanying drawings, in which:

Figure 1 is an end elevational view of an ironing machine embodying the features of the invention.

Fig. 2 is a fragmentary side elevational view, partly in section, of the machine shown in Fig. 1.

Fig. 3 is a side elevational view on a reduced scale and showing the machine when placed on a table.

Fig. 4 is an end elevational view on a reduced scale with the machine placed on a table.

Fig. 5 is a fragmentary sectional view taken on the line 5—5 of Fig. 1.

The present application is a continuation-in-part of my copending application Serial No. 540,672, filed June 16, 1944.

The ironing machine shown in the present application as well as in the above-referred-to copending application comprises a base 10 provided with a head structure, indicated generally at 11, secured to the base adjacent one end

thereof and extending upwardly therefrom. Mounted on a shaft carried by the head 11 is an ironing element in the form of a roll 12 provided with the usual padding and on which the articles to be ironed are placed. Cooperating with the roll 12 is a second ironing element in the form of a shoe 13 shiftable supported by an arm 14 for movement toward and from the roll. The arm 14 is carried by a rockshaft 15 located in and extending lengthwise of the base 10. While in the structure herein shown, the shoe is the shiftable element, the invention is of such scope as to cover a machine in which the roll is shiftable.

In the specific structure shown in my copending application, the head 11 comprises a supporting member 16 enclosed by a shroud 17 of any preferred external appearance and design. The supporting member 16 has its upper end formed as part of a motor casing 20 to support a motor 21, and has secured thereto a gear casing 22. To drive the roll, the motor 21 has a shaft provided with a pinion 23 meshing with a gear 24 mounted on a shaft 25. The shaft 25 is provided with a pinion 26 meshing with a gear 27 loosely mounted on a stub shaft 30. The gear 27 is adapted to be connected by a clutch 31 to the shaft 30. The shaft 30 has rigidly formed thereon a pinion 32 meshing with a gear 33 mounted on the roll-supporting shaft, indicated at 34. Thus, when the clutch 31 is connected, the roll will be driven at a reduced speed by the motor 21.

The motor is also utilized to effect shifting movement of the shoe 13 toward and from the roll 12. To this end, the shaft 25 is provided with a second pinion 35 meshing with a gear 36 loosely mounted on a shaft 37. Also mounted on the shaft 37 and rotatable with the gear 36 is a toothed member 40. Secured to the shaft 37 adjacent the toothed member 40 is a disk 41 carrying a clutch finger 42 adapted to engage the toothed member 40 under control of the operator. Thus, when the finger 42 is in engagement with the toothed member 40, the shaft 37 is rotated.

The shaft 37 also carries a pinion 43 meshing with a cam drive gear 44 secured to a shaft 45. The shaft 45 also carries a four-lobed cam 46 adapted, when rotated, to swing a lever 47 mounted on a hollow shaft 50. The lever 47 is pivotally connected to an intermediate lever 51 secured to a rockshaft 52. The rockshaft 52 projects through the wall of the gear casing and at its outer end is provided with a lever 53 connected by a link 54 to a shoe-actuating lever 55.

A spring 56 is connected to the pivotal connection of the link 54 and the lever 55 and tends to hold the lever 47 in engagement with the cam 46. The shoe-actuating lever 55 is bent to extend downwardly into the base 10 and is connected to the rockshaft 15 for carrying the shoe toward and from the roll. An energy-storing device, indicated generally at 57, is mounted in the gear casing to cooperate with the cam 46 to compensate for and counter-balance the effect of a spring 58 in the shoe-supporting arm 14 so that such spring will not tend to cause an over-drive of the cam 46 when the shoe moves away from the roll and will not place an excessive load on the drive when the shoe is moving toward the roll.

The engagement of the roll clutch 31 as well as the engagement of the clutch finger 42 with the toothed member 40 is under the control of the operator. To this end, a rockshaft 60 extends into the gear case through the tubular shaft 50 and at its inner end is provided with an operating member 61. The operating member 61 is provided with a first arm 62 adapted to engage one arm 63 of a bell crank 64. The other arm of the bell crank 64 engages the roll clutch 31 to shift it out of engagement, a spring (not shown) being provided to effect engagement of such clutch. The bell crank 64 is also adapted to be held in clutch-disengaging position by an extension 65 on the end of the pivotal connection between the levers 47 and 51 when these two levers are so positioned that the shoe 13 is out of engagement with the roll. Thus, the roll will be stopped when the shoe is out of engagement therewith.

The operating member 61 has a second arm 66 adapted to engage a cam portion 67 on a disengaging member 70 for disengaging the finger 42 from the toothed member 40. The disengaging member 70 normally lies in the path of the finger 42 to hold the finger out of engagement with the toothed member 40, but when the disengaging member 70 is shifted out of the plane of the finger 42, a spring causes the finger 42 to engage the toothed member 40 and thus effect rotation of the cam 46. The operating member 61 is adapted to be manually shifted to effect movement of the disengaging member 70 out of the plane of the clutch finger and then to be released so that, when the clutch finger 42 has made one revolution, it is reengaged by the disengaging member 70 and shifted out of engagement with the toothed member 40.

In the normal operation of the machine, the operating member 61 is rocked to first effect a disengagement of the roll clutch 31 and thereafter to move the disengaging member 70 out of the plane of the finger 42 to effect shifting movement of the shoe in one direction or the other. When it is desired to use the machine for pressing with the shoe 13 in engagement with the roll 12 but with the roll stopped, the operating member 61 is held in such position that the first arm 62 thereon holds the bell crank 64 in such position as to disengage the roll clutch 31. The operating member 61, however, is not moved far enough to cause the second arm 66 thereof to effect shifting of the disengaging member 70. Thus, the shoe 13 may be in engagement with the roll 12 but the roll may be held against rotation since its clutch 31 is thereby disengaged.

The present invention relates to the means for manually operating the rockshaft 60. The latter

is provided at its outer or right-hand end with an arm 71. The free end of the arm 71 is connected by a downwardly extending link 72 to one corner of a triangularly shaped piece 73 located in the lower part of the head 11 and extending downwardly into the base 10. The triangular piece 73 is carried on a rockshaft 74 extending horizontally from front to rear of the machine and journaled in the supporting member 16.

The rockshaft 74 is adapted to be operated by a hand lever which may be connected to the rockshaft in any of a plurality of positions so that the hand lever may be operated in different ways convenient to the handling of different types of articles on the machine. For handling small articles, such as handkerchiefs or the like, only one hand is needed to hold the article on the roll as it enters into the ironing space so that the hand lever may extend up and adjacent the roll for the operator to actuate it with her other hand. For wide articles that extend beyond the ends of the roll, the hand lever, when in such position, would be covered by the article being ironed. Therefore, it is more convenient to have the hand lever extend outwardly away from the roll beyond the head 11 in such case. At other times, the operator would prefer to use both her hands for feeding the article into the ironing position, so that the hand lever may then be positioned for operation by her elbow. If the ironing machine is placed on the table and the operator is seated in front of the table, knee operation of the machine is frequently the most convenient.

In order to provide a hand lever capable of being connected to the machine in these various positions, I construct the hand lever and the rockshaft 74 so that they are readily separable and the hand lever may be secured to the rockshaft in these various positions. To this end, the hand lever, which is indicated generally at 75, is formed of a round rod comprising a shank portion 76 adapted to be inserted through a hole in the front wall of the shroud 17. The rockshaft 74 is made tubular in form, of round cross section, to receive the shank portion 76 of the hand lever, as illustrated in Figs. 1 and 5. To connect the hand lever to the rockshaft 74, the inner end of the latter is provided with a polygonal socket 80 which is hexagonal in the present instance. The inner end of the shank 76 is drilled as at 81 and a short piece of hexagonal rod 82 is driven into the drilled socket 81. The hexagonal rod 82 extends beyond the end of the shank portion 76 for insertion into the hexagonal socket 80. Thus, the shank portion 76 of the hand lever may be inserted in the rockshaft 74 in a variety of positions spaced 60 degrees apart.

The outer end of the hand lever 75 is bent at a right angle to the shank portion 76, as indicated at 83, and is further bent at 84 to extend rearwardly and at an angle to the plane of the portions 76 and 83. On the end of the handle beyond the bend 84, a hand grip portion 85 of plastic material or the like may be secured.

In Figs. 3 and 4 I have illustrated the various positions of the hand lever, referred to above, whereby it may be operated in different ways. Thus, in the full-line position 90, as shown in Fig. 3, the hand lever is adapted for operation by the hand when wide articles extending over the head 11 are to be ironed. In this position, the hand grip portion 85 is located beyond the head and thus substantially beyond the article being ironed. When the hand lever is mounted in the

position indicated at 91, the hand grip portion 85 extends closely adjacent the end of the roll and is convenient for use when small articles are being ironed. When the hand lever is mounted in the position indicated at 92, the hand grip portion 85 extends downwardly adjacent the front of the roll and may be easily actuated by the operator's right elbow when she is using both of her hands in placing the article to be ironed on the roll. For knee operation, the hand lever occupies the position indicated at 93 so that the lever extends forwardly over the front edge of the table and then downwardly and rearwardly under the table, as is illustrated in Fig. 4. The hand grip portion 85 may then be readily actuated by the operator's knee when she is using both her hands in manipulation of the articles to be ironed.

The machine is also constructed so that provision is made for foot operation, if desired. To this end, the triangular piece 73 is provided with a forwardly bent lug 100 to which a cable or operating wire 101 may be secured. The wire is adapted to extend outwardly through the end of the base 10 and a flexible casing, indicated at 102, surrounding the wire may be detachably secured at one end within the base. The wire 101, being flexible, may extend downwardly to any desired position on the floor and be provided there with a suitable treadle (not shown) for operating it. The wire 101 and the treadle may be made as a separate attachment for the machine, to be sold as an accessory therefor, the machine merely being provided with an aperture in the base through which the end of the wire and its casing may be inserted.

From the foregoing description, it will be apparent that I have provided a novel control member for an ironing machine, which member may be readily adjusted into any of a plurality of positions to permit actuation thereof by the operator in a manner most convenient for the particular ironing work being performed. The control member comprising the hand lever 75 may be positioned in either of the two positions 90 or 91 for hand operation, or in position 92 for elbow operation, or in position 93 for knee operation. When in the latter position, the hand lever may extend downwardly over the front edge of a table on which the machine rests and thence rear-

wardly under the table so as to be in convenient position for engagement by the operator's knee when she is sitting in front of the table operating the machine. The machine illustrated also provides for convenient attachment of a foot control device when such mode of operation is desired.

I claim:

An ironing machine comprising, in combination, a base, a head at one end of said base, a pair of relatively shiftable ironing elements, one being supported by said head, power operated mechanism supported by said head for shifting one of said elements toward and from the other, control means for said mechanism including a rotatable socket member mounted in the lower part of the head on an axis extending from the front to the rear of the machine, said socket member being adapted to receive a handle extending into said head from the front thereof, an actuating lever mounted on said socket member and extending into said base, an operative connection extending between said lever and said mechanism, and a foot-controlled cable insertable into said one end of said base and connectible with said lever.
